PAPER FASTENER

Herbert D. Lawson, Washington, D. C.

Application January 13, 1943, Serial No. 472,241

16 Claims. (Cl. 24—153)

This invention relates to paper fasteners of the type utilizing spaced bendable fingers extended from a base and insertable through spaced openings in sheets of paper or the like to be held together. In known structures the fingers are also extended through clamping plates and after being bent down or folded onto the plates, are secured by slides or like fasteners usually carried by said plates. Most articles of this class have been made of metal. Due to present scarcity of this material, however, various substitutes have been developed but with little success because of their fragile nature and/or the difficulties encountered in fastening the retaining fingers in folded positions.

An object of the present invention is to make a fastener of the two finger type which does not require the use of metal, can be manufactured mainly of paper or stiffened fabric stock, and utilizes tie devices for fastening the ends of the fingers together while in folded positions.

Another object is to reinforce the fastener with a tie element the end portions of which constitute the tie devices.

A further object is to provide a fastener which can be affixed readily to a backing or supporting sheet, such as a portion of a file wrapper, so that it is thus possible to apply the fastener at any point without perforating the sheet to which it is applied.

A still further object is to provide a fastener which can be produced from sheet material without waste of stock.

Another object is to reinforce the fingers to resist wear and breakage, said fingers, however, being free to flex sufficiently to insure convenient bending wherever desired.

A further object is to secure the tie element to the fastener in an efficient manner whereby accidental separation thereof is avoided during ordinary use of the fastener.

With the foregoing and other objects in view which will appear as the description proceeds the invention consists of certain new and novel details of construction and combinations of parts and in certain steps in the method hereinafter more fully pointed out, it being understood that various changes may be made in the construction and method disclosed without departing from the invention as claimed.

In the accompanying drawing the preferred forms of the invention have been shown.

In said drawing

Figure 1 is a bottom plan view of a blank from which the fastener is to be formed.

Figure 2 is a similar view showing the tie element applied to the blank, this being the second stage in the method of construction.

Figure 3 illustrates the third step of the method of construction, the fingers being folded in part onto the adjacent portions of the tie element.

Figure 4 is a bottom plan view of the completed fastener.

Figure 5 is an enlarged section on line 5—5, Figure 4.

Figure 6 is a front elevation showing the fingers of the fastener in position to thread the tie element through papers to be secured, a clamping strip, such as used on the topmost sheet of a fastened stack of papers being shown partly positioned on the fingers.

Figure 7 is a similar view of the fastener in holding position, sheets of paper and the top strip being held thereby.

Figure 8 is a bottom plan view of a modified form.

Figure 9 is a bottom plan view of an attaching tab through which the fingers of the fastener can be threaded.

In manufacturing this fastener a sheet of stock, which can be paper of proper weight, stiffened fabric or the like, is cut into strips, one of which is indicated at 1. Incisions are formed in the side edges as at 2 and longitudinal weakening lines or scores are pressed into the material along lines preferably parallel extending to the free ends of the strip from the inner end of the incisions. These have been indicated at 3'. Thus end arms 3 are provided each of which has side portions 4 and 5. A length of cord 6 is placed longitudinally along the center of the strip so that its ends will project beyond the ends of the arms and this cord is attached to the strip by an adhesive 7 which can first be applied to the bottom surface of the strip.

After the cord has been placed, the side portions 5 are folded onto the cord and arms 3, and thereafter the portions 4 also are folded over and compressed, these portions all being held together by the adhesive. Thus each arm is formed of lapping thicknesses and is in effect a flat tube with a cord extending therethrough.

The fasteners can be shipped flat, together with clamping strips 8 of stiff paper or like stock having spaced openings to receive the fingers.

In using a fastener in a file wrapper, for example, spaced openings can be punched through a

portion of the wrapper and the fingers inserted therethrough. Thereafter the similarly punched papers P and a top strip 8 to be secured, are placed on the fingers which thus act to thread the ends of the tie cord through the openings as indicated in Figure 6. The looped portions of the tie cord are then pulled to withdraw the ends of the cord from the openings after which the cord is drawn taut and tied, as at 9, thereby bending the fingers down onto strip 8 and holding them in retaining positions.

Bending of the fingers can be facilitated by pressing transverse creases 4' therein while the fingers are being shaped and compressed. Instead of threading the fingers through spaced openings in the file wrapper or other backing, the gummed bottom surface 7 of the base member can be affixed to said backing or, if preferred, the base member 10 can be enlarged to provide an attaching tab 11 as in Figure 8, said tab being provided with an adhesive 7 for holding it in place.

Another modification has been shown in Figure 9 wherein an attaching tab 12 is made separate from the base of the fastener but has openings 13 for receiving the fingers of the fastener. This tab has an adhesive 14 for holding it to a backing sheet or the like.

What is claimed is:

1. A fastener for holding together paper sheets or the like including a base member, fingers extending therefrom for insertion through spaced apertures in superposed sheets of material to be fastened together, and tie devices extended from said fingers.

2. A fastener for holding together superposed paper sheets or the like having spaced openings, which includes a base member, tie devices connected to said member, and bendable means on said member for thrusting said devices through the openings.

3. A fastener for holding together superposed sheets or the like having spaced openings, including a base member, bendable fingers thereon positioned for insertion through the respective openings, and tie devices extending from the free ends of the fingers.

4. A fastener for holding together superposed paper sheets or the like having spaced openings, including a base member, bendable fingers thereon positioned for insertion through the respective openings, and tie devices extending from and secured to the fingers, said fingers constituting means for thrusting the devices through the openings.

5. A fastener for holding together superposed sheets of paper or the like including a base member, bendable fingers extending therefrom, a marginal stiffening fold on each finger, and a tie device secured to and extending from each finger.

6. A fastener for holding together superposed sheets of paper or the like including a base member, substantially flat tubular fingers extending

therefrom and tieing means partially housed within and extending from the fingers.

7. A fastener for holding together superposed sheets of paper or the like including a base member, each finger having inturned marginal stiffening portions, and tieing means between said portions and the fingers and extending therebeyond.

8. A fastener for holding together superposed sheets of paper or the like including a base member, bendable fingers extending therefrom, a marginal stiffening fold on each finger, and a tie device secured to and extending from each finger, said fingers having transversely weakened portions to facilitate bending.

9. A fastener for holding together superposed sheets of paper or the like having spaced openings, including a base, fingers extended therefrom, each including lapping thicknesses of material, and tie devices retained between said thicknesses of material and extending from the fingers.

10. A fastener of the class described including a base, fingers integral with the base including lapping thicknesses of material and a length of tie material extending along one surface of the base and between and beyond the thicknesses of the fingers.

11. A fastener including a base, an adhesive on the base, spaced fingers integral with the base, and a tie device affixed to the base and fingers and extending beyond the free ends of the fingers.

12. A fastener made of paper stock or the like including a base, fingers integral with the ends thereof each finger having a lapping portion extending longitudinally thereof, and a cord having a portion held between each finger at its lapping portion and constituting a tie.

13. A fastener made of paper stock or the like including a base, bendable fingers integral with the ends thereof, and a cord secured along the bottom of the base and along and beyond the free ends of the fingers, said cord constituting a tie.

14. A fastener made of paper stock or the like including an attaching tab having an adhesive on one face and spaced apertures, a base, fingers integral with the base and extended through the apertures, and a cord extended along and beyond the fingers to constitute a tie.

15. A fastener made of paper stock or the like including an attaching tab having an adhesive on one face and spaced apertures, a base, fingers integral with the base and extended through the apertures, a top strip having spaced apertures through which the fingers are extended, and a cord extending along and attached to the fingers and extending therebeyond, said cord constituting a tie.

16. A fastener made of paper stock or the like including an attaching tab having an adhesive on one face and spaced apertures, a base, fingers integral with the base and extended through the apertures, and a tie cord carried by the free end portion of each finger.
